(57) **CLAIM**

The ornamental design for a magnetic mounting system, as shown and described.

DESCRIPTION

FIG. 1 is a top perspective view of a magnetic mounting system showing our new design.

FIG. 2 is a bottom perspective view thereof;

FIG. 3 is a top plan view thereof;

FIG. 4 is a right side view thereof;

FIG. 5 is a left side view thereof;

FIG. 6 is bottom plan view thereof;

FIG. 7 is a front view thereof; and,

FIG. 8 is a rear view thereof.

The broken lines in the drawings are included for the purpose of illustrating portions of the article and form no part of the claimed design.
